UNITED STATES PATENT OFFICE

WILLIAM LOUIS BESSOLO, OF DENVER, COLORADO

PIPE-WRENCH.

1,004,792.

Specification of Letters Patent.

Patented Oct. 3, 1911.

Application filed October 29, 1910. Serial No. 589,676.

To all whom it may concern:

Be it known that I, WILLIAM LOUIS BESSOLO, a citizen of the United States, residing in the city and county of Denver and State 5 of Colorado, have invented certain new and useful Improvements in Pipe-Wrenches; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to improvements in pipe wrenches, my object being to provide a device of this character which shall be simple in construction, economical in cost, reliable, durable and efficient in use, and to 20 this end the invention consists, generally speaking, of a handle or shank member upon which is mounted a jaw member in such a manner that it has a limited degree of rocking movement. With this rocking jaw 25 member is pivotally connected a jointed or flexible coöperating member exteriorly toothed to interlock with a spring-actuated pawl also pivotally mounted on the shank or handle member adjacent the rocking jaw 30 member. When the rocking jaw member is moved in one direction the coöperating jaws are made to tightly grip the pipe interposed between them, through the instrumentality of the spring-actuated pawl, while when the 35 rocking member is moved in the opposite direction the space between the jaw is enlarged sufficiently to allow the wrench to be turned on the pipe in the reverse direction from the operating movement in order to 40 get a new hold.

My improved wrench may be used as a vise when mounted in a suitable support, for the purpose of holding a part in place for any purpose.

45 Having briefly outlined my improved construction, I will proceed to describe the same in detail, reference being made to the accompanying drawing in which is illustrated an embodiment thereof.

50 In this drawing: Figure 1 is a view of my improved wrench showing the flexible jaw open and the pipe laid upon the rocking jaw ready to be engaged by the flexible jaw when thrown into coöperative relation with 55 the rocking jaw. Fig. 2 is a similar view illustrating both jaws in coöperative rela-

tion with the pipe. In this view two positions of the wrench are illustrated, one being the pipe-gripping position in full lines and the other the pipe-releasing position, 60 which is indicated by dotted lines. Fig. 3 is an edge view of the wrench or a view looking at right angles to Fig. 2, viewed in the direction of arrow 3, Fig. 2. Fig. 4 is a view similar to Fig. 2, but on a smaller 65 scale, and showing the wrench used as a vise, the same being mounted in a holder secured to a stationary member. Fig. 5 is a side elevation of the wrench partly in section, the parts being shown in the pipe-gripping position, the shank adjacent the 70 rocking jaw being shown partly in section. Fig. 6 is a side elevation of the wrench illustrating a modified form of construction, the scale being approximately the same as in 75 Figs. 4 and 5. Fig. 7 is a detail view of the spring-retained pawl. Fig. 8 is an edge view of the same. Figs. 9 and 10 illustrate edge and side views respectively of the links forming a part of the flexible jaw of 80 the form of construction shown in Fig. 6. It will be noted that Fig. 9 is a view looking in the direction of arrow 9, Fig. 10. Figs. 11 and 12 are side and edge views respectively of the links forming a part of the 85 flexible jaw in the form of construction shown in Figs. 1 to 5 inclusive.

The same reference characters indicate the same parts in all the views.

Referring first more especially to the construction illustrated in Figs. 1 to 6 inclusive and Figs. 11 and 12, let the numeral 5 designate the shank of the wrench, which has a curved semicircular socket 6 at its upper end, and a bifurcated extension 7 projecting 95 upwardly from the said socket, the same being composed of two members 8 between which a pawl 9 is pivoted, the pawl being secured in place by a rivet 10. This pawl is engaged by a leaf spring 12 whose lower 100 extremity is secured to the upper part of the shank as shown at 13. This spring is passed through between the arms 8 of the bifurcated member 7 and caused to engage the pawl 9 on its lower edge. In this specification the terms "upper" and "lower" 105 must be understood as applied to the wrench when it occupies a vertical or what may be termed the upright position, which it is assumed to occupy in the various views of 110 the drawing.

The socket 6 of the shank or handle of

the wrench is engaged by the lower semi-circular extremity 14 of a jaw 15 which is connected with the shank by a rivet pin 16. This jaw is also bifurcated, its lower extremity straddling a tongue 17 which projects upwardly from the bottom of the socket 6. In fact the jaw 15 as illustrated in the drawing is composed of two distinct parts or members 18, which are perhaps best illustrated in Fig. 3. These members are provided with shoulders 19 which engage similar shoulders 20 formed on the shank 5. The members 18 of the jaw 15 lie in the same planes with the members 8 of the extension 7 and the jaw 15 has a limited degree of rocking movement, the shoulder 20 forming a stop in one direction, and the members 8 of the extension 7 forming a stop in the opposite direction.

The pawl 9 passes between the members 18 of the jaw 15 and its curved pointed extremity 21 is adapted to engage teeth 22 formed on the outer edge of a curved jaw member 23 whose inner edge is toothed as shown at 24 to grip the pipe 25. This toothed member 22 is connected with the jaw member 15 by means of two links 26 and 27 respectively, the link 26 consisting of a single member having one extremity connected with the jaw 15 by a rivet 28 which is passed through the link 26 and also both members 18 of the jaw 15, the last named members, however, being reinforced as shown at 29 to give increased strength to the jaw at this point. The link 27 consists of two members 30 which are pivotally connected with the link 26 by a rivet pin 31, while their opposite extremities are pivotally connected as shown at 32 with the curved jaw 23. These jaw links 26 and 27 give flexibility to the jaw structure which co-operates with the rocking jaw 15. The said links are toothed on their inner edges as shown at 33 and 34, to harmonize with the teeth 24 of the jaw member 23. The upper faces of the members 18 of the jaw 15 are also toothed as shown at 35, the said toothed faces being upwardly inclined from the pivot pin 28 and arranged to co-operate with the toothed faces of the links 26 and 27 and the jaw member 23, when the parts are in the position illustrated in Figs. 2 to 5 inclusive.

When the device is in use and it is desired to cause it to grip the pipe 25 for instance, the latter may be placed first in the position shown in Fig. 1 when the flexible jaw structure is open. This last named structure may then be thrown upwardly to engagement with the pipe, in which event the rocking extremity of the pawl 9 is pushed downwardly and caused to engage the exterior teeth 22 of the jaw member 23 (see Fig. 2).

It may be assumed that the normal position of the jaw member 15, or rather of the

handle member 5, with relation to the jaw member when the jaw structure is applied to a pipe as in Figs. 2 to 5 inclusive, is that illustrated by the dotted position of the handle in Fig. 2, since the spring 12 acting on the pawl 9 has a tendency to move the entire jaw structure as far as possible in the direction of the arrow A in Fig. 2. This is particularly the case if we assume that the device is employed as a vise as illustrated in Fig. 4, since in this event the handle member must remain stationary, while the jaw structure is actuated by the spring-pressed dog 9 to cause the jaw member 15 to move as far as possible toward the right or in the direction of arrow A. When in this position the pipe is released by the jaws. Now when it is desired for the jaws to grip the pipe to prevent the latter from turning, the jaw structure is moved in the direction opposite the arrow A in Figs. 2 and 4, causing the parts to assume the full line position in the said views. The pipe is then tightly gripped and cannot be turned within the jaw structure. As soon as the force is released which holds the said structure in the full line position, the spring-actuated pawl 9 will return the said structure to its limit of movement in the direction of arrow A in the said figures. In other words, if we assume that the vise form of the device is employed, we must assume that the jaw 15 with its attachments rocks back and forth from its limit of movement toward the right where it is stopped by the members 8 of the handle extension 7, and toward the left by the shoulders 20 formed on the handle as heretofore explained. However, if it is used simply as a wrench acting upon a pipe which is stationary, same being held so in the vise structure or supported in any other suitable manner, the handle 5 will be moved back and forth from the dotted line or released position in Fig. 2 to the full line or gripping position in the same figure. In any event the result is the same. It will be observed that when the handle member is moved from the full line position to the dotted line position in Fig. 2 that the jaw structure is slightly expanded in a direction to release the pipe, the degree of expansion being the distance between the full line position of the toothed edge of the jaw part 23 and the dotted line position of the same teeth in Fig. 2; while when the handle is moved in the opposite direction or to the full line position, the pawl 9 is acted upon in such a way as to tighten the jaw structure upon the pipe by moving the said structure from the dotted line to the full line position in said figure.

In the form of construction illustrated in Fig. 6, the handle 5 of the jaw 15 is substantially the same as illustrated in the other views. However, the jaw structure co-

operating with the jaw 15 consists of a chain 36 having one of its end links 37 pivotally connected with the jaw 15 as shown at 38. Any desired number of the links of the chain 36 may be exteriorly toothed as shown at 39 to engage the pawl 40, which is provided with a rigid pin 41 adapted to enter recesses 42 formed in the parts 8 of the extension 7 of the handle member. Two sets of notches are illustrated whereby the pawl 40 may be adjusted. The extremity of the jaw adjacent the pin 41 is acted upon by a leaf spring 43 which is secured to the handle by means of a screw 44. This spring 15 serves to retain the pawl in place and also serves to maintain the pawl in operative relation with the teeth 39 of the chain. This form of construction operates in substantially the same way as that heretofore described when referring to the other forms. It may be stated, however, that by making the flexible jaw structure of a chain or a series of relatively short pivotally connected members, the flexible jaw structure is 25 caused to fit the pipe with greater accuracy. In other words, by virtue of this construction practically the entire inner surface area of the flexible jaw member may be caused to engage the pipe to which the wrench is applied. The links of the chain 36 are toothed on their inner surfaces as shown at 45, the teeth being positioned to grip the pipe when the wrench is operated in a certain direction.

35 In the construction illustrated in Fig. 4 in which my improved device is employed as a vise, a holder 46 is used to support the wrench. This holder may, of course, be of any suitable construction. As illustrated in 40 the drawing it consists of two clamping members 47 and 48 which are hinged at 49 and engage a stationary part 50, which may form a part of a bench, table or other suitable support sufficiently stable for the purpose. The jaw members 47 and 48 are clamped to the part 50 by means of a bolt 51 which passes through openings formed in both jaws, a wing nut 52 being applied to the threaded extremity of the jaw for 50 tightening purposes.

Having thus described my invention, what I claim is:

1. The combination of a handle, a jaw mounted to have a limited degree of rocking movement thereon, and the handle having a bifurcated extension beyond the pivot of the jaw, a pawl pivotally connected with the handle extension and located between the arms of its bifurcated portion, the pawl 55 being spring-actuated and the rocking jaw being also bifurcated to allow the pawl to pass between its members, and a second jaw pivotally connected with the first named jaw and exteriorly toothed to receive the 60 pawl, substantially as described.

2. In a pipe wrench the combination of a handle having a semicircular socket at its forward extremity, a tongue centrally mounted in the socket, a jaw bifurcated to straddle the tongue and having its rear 70 extremity in engagement with the socket and constructed to have a limited degree of rocking movement therein, the handle having a bifurcated portion extending forwardly beyond the said socket, a pawl passing through the bifurcated portion, the said handle extension being pivotally connected therewith, the said pawl being spring-actuated, and a flexible jaw pivotally connected with the first named jaw and exteriorly 75 toothed to interlock with the pawl, the flexible jaw being adapted to pass through between the parts of the bifurcated jaw, substantially as described.

3. In a pipe wrench, the combination of a 80 handle, a jaw connected with the handle to have a limited degree of rocking movement, a bifurcated extension located above the handle beyond the pivot of the jaw, a second jaw pivotally connected with the first named 85 jaw, and a pawl pivotally mounted on the handle extension and adapted to interlock with the second jaw which is fashioned for the purpose.

4. In a pipe wrench, the combination of a 90 handle and an extension located above the handle and extending at angles thereto, a jaw connected with the handle below the extremity of the extension and arranged to have a limited degree of rocking movement, a second jaw pivotally connected with the first named 95 jaw, and a pawl pivotally mounted on the handle extension and adapted to interlock with the second jaw.

5. The combination of a handle member, 100 and an extension located at one extremity of the handle member and extending at an angle thereto, a jaw pivotally connected with the handle member below the extremity of the extension and arranged to have a 105 limited degree of rocking movement, a curved jaw pivotally connected with the first named jaw and arranged to coöperate therewith, and a spring actuated pawl pivotally mounted on the handle extension and adapted to engage the curved jaw, for the 110 purpose set forth.

6. The combination of a handle member, 115 and an extension located at one extremity of the handle member and extending at an angle thereto, a jaw pivotally connected with the handle member below the extremity of the extension and arranged to have a 120 limited degree of rocking movement, the extension being adapted to limit the movement of the jaw in one direction, a spring-actuated pawl connected with the said handle extension, and a second jaw 125 pivotally connected with the first named jaw and co-operating therewith, the second jaw being 130

fashioned to interlock with the pawl, for the purpose set forth.

7. In a pipe wrench, the combination with a handle, and an extension located at one extremity of the handle, of a jaw connected with the handle below the extremity of the extension and arranged to have a limited degree of rocking movement, the extension being adapted to limit the movement of the

10 jaw in one direction, a second jaw pivotally

connected with the first named jaw, and a pawl pivotally mounted on the handle extension and adapted to interlock with the second named jaw, substantially as described.

In testimony whereof I affix my signature 15 in presence of two witnesses.

WILLIAM LOUIS BESSOLO.
